HENRY M. QUINCEY, OF LOS ANGELES, FREDERICK J. SIENKNECHT, OF NORDHOFF,
AND MICHAEL J. DONAHOO, OF LOS ANGELES, CALIFORNIA.

IRRIGATION-DITCH CLEANER.

1,245,271.

Specification of Letters Patent.

Patented Nov. 6, 1917.

Application filed March 27, 1917. Serial No. 157,663.

To all whom it may concern:

Be it known that we, HENRY MERRIAM QUINCEY, FREDERICK J. SIENKNECHT, and MICHAEL J. DONAHOO, the first a subject of 5 the King of Great Britain and the two latter citizens of the United States, residing at Los Angeles, Nordhoff, and Los Angeles, respectively, in the counties of Los Angeles, Ventura, and Los Angeles, respectively, and 10 State of California, have invented new and useful Improvements in Irrigation - Ditch Cleaners, of which the following is a specification.

This invention relates to excavating machinery and particularly pertains to a machine for cleaning irrigation ditches and the like.

In the parts of the country where it is necessary to irrigate the agricultural lands, 15 ditches are formed to carry water to the different districts. These ditches are usually formed with earth walls and it is very easy for vegetation of various sorts to grow in the ditch and also for the side banks to 20 gradually fill the channel. Ordinarily such ditches must be cleaned manually at given periods and this, of course, requires considerable time and much expense. It is the 25 principal object of this invention to provide 30 a mechanically operated ditch cleaning machine which will rapidly and inexpensively clean the ditch of vegetation and rebuild its banks.

Another object of this invention is to provide means whereby the soil carried from the ditch will be directly delivered to the opposite sides thereof in a manner to increase the depth of the ditch and aid in preventing the erosion of the soil thereafter.

Another object of this invention is to provide a machine of the above class which is adapted to travel along the ditch irrespective of the quantity of water therein and which is further provided with means for 45 maintaining the machine in a horizontally aligned position.

Another object of this invention is to provide means whereby the machine may be steered as it is drawn along the ditch.

It is a further object of this invention to 50 provide a device of the above class which embodies a power plant and excavating means mounted in a single unit and adapted to be driven and controlled in a simple manner.

Other objects will appear hereinafter.

The invention is illustrated, by way of example, in the accompanying drawings in which:

Figure 1 is a view in plan illustrating the 60 entire device with parts broken away for the sake of convenience.

Fig. 2 is a view in side elevation illustrating the machine and particularly disclosing the power plant and the steering 65 means.

Fig. 3 is a view in end elevation illustrating in a diagrammatical manner the operation of the device.

Referring more particularly to the drawings, 10 indicates the body of the machine. This body is preferably formed of sheet metal and in reality is a boat or skid, having end walls 11 and 12 and a continuous bottom closed by the end walls. The bottom 70 of the skid is substantially the shape of the ditch and is here shown as having its sides inclined at an angle to the vertical of approximately sixty degrees. In case there is sufficient water in the ditch the machine will 75 float, or partially float, and if the water is too low to float the machine it may be slid along the ditch as it rests upon its smooth sides. The shape of the body serves to restore the ditch to its desired shape. Mounted 80 at the forward end of the body is a pair of conveyers 13 and 14. These elements are each formed of a pair of sprocket chains 15 and 16 which are led over shafts 17 and 18. The shafts 18 are positioned at the bottom 90 of the body and parallel to each other. The shafts 17 are supported by suitable framework above and at the opposite sides of the body, as particularly shown in Fig. 3 of the drawings. Mounted beneath the chains are 95 inclined floors 19 and 20 which correspond in their angular disposition to the side walls of the body and also lie substantially parallel to the chains which pass over them. The shape of these floors in cross-section, 100 combined with the shape of the body in cross-section serves to give a corresponding and desired shape to the ditch and its banks. The forward edges of these floors are beveled, as indicated by the numerals 22 and 23 105 of Fig. 1. This permits the sides of the ditch to be cleaned away and scraped as the machine is drawn forward by means of a cable 24 secured at the forward end of the machine. As the machine is drawn forward, 110

the soil cut and loosened by the beveled edges of the floor members 19 and 20 will be carried on to this floor and elevated by elevating flights 25 which are secured at their 5 opposite ends between the sprocket chains 15 and 16 and are adapted to move therewith.

The sprocket chains are simultaneously driven by a power plant 26 which is here 10 shown as an internal combustion engine. This engine is mounted upon the machine body at its rear end and drives the conveyer mechanism by a suitable transmission. The driving transmission comprises a driving 15 gear 27 directly connected to the crank shaft of the engine, a driven gear 28 in mesh therewith, and a transmission shaft 29. The gear 28 is mounted upon this shaft and rotates it to transmit power to 20 a pair of parallel drive shafts 30 and 31 mounted at the forward end of the machine body. These shafts are fitted with sprockets 32 and 33 which in turn drive chains 34 and 35, by which the conveyer chains 15 and 16 25 are driven upon rotation of the shafts 17.

As a means for holding the conveyer chains taut, a pair of idler shafts 36 and 37 are provided. These shafts are pivotally supported at one end upon bearings 38 and 39 which are formed integral with swinging arms 40 and 41 loosely mounted upon the shafts 30 and 31. The outer ends of the idler shafts are secured to each other by brackets 42 and 43 which are adjustably 35 connected by a turn-buckle 44. Rotatably mounted upon the shafts 36 and 37 are pairs of sprockets 45 and 46 which are engaged by the upper lengths of the conveyer chains 15 and 16 and support said chains in a firm 40 manner.

In order to insure that the conveyers will bear the same or a desired angular relation to the vertical, a pair of stabilizer plates 47 and 48 are provided. These plates are pivotally mounted at the opposite sides of the body of the machine upon brackets 49 and 50, respectively, and extend outwardly and upwardly and are adapted to bear upon the new formed banks as the machine moves 45 forwardly. Before starting, the stabilizers bear upon the old banks and are adjusted to start the work at the desired angle. Supporting arms 51 extend upwardly from each of the plates and are connected with pitman 50 rods 52, the opposite ends of which are pivotally secured to crank arms 53 and 54. These arms are mounted to rotate with shafts 55 and 56, respectively, by which the vertical 55 adjustment of the plates is simultaneously obtained. An adjusting wheel 57 is provided to actuate each of these shafts.

To insure that the machine will readily move along the ditch, it is provided with a 60 prow 58. This prow is formed with sides 65 which vertically and horizontally taper from

the bottom and center of the machine and which form a bottom cutting and separating member adapted to force its way into the soil at the bottom of the ditch and more readily travel therewith. Acting in combination with this prow is a rudder 59 by 70 which the prow is directly guided and the direction of movement of the machine is determined. The rudder is pivoted for horizontal movement upon a vertical shaft 60. 75 The rotation of this shaft is controlled by a steering wheel 61. The wheel 61 is mounted at the end of a steering shaft 62 which rotates a worm gear 63 in mesh with a worm wheel 64 fixed at the upper end of the vertical shaft 60.

In operation, the machine is placed within an irrigation ditch to be cleaned and the cable 24 at its forward end connected with a suitable mechanism by which it is wound. 80 The machine will rest with the smooth sides of the body member supported by the walls of the ditch and as the cable 24 is wound the entire device will advance along the ditch. The prow 58 will rest upon the bottom of the ditch and tend to form a furrow therewith. Simultaneously, the beveled edges 22 and 23 of the angular floor members 19 and 20 will cut into the sides of the ditch and cause the soil to pass over 85 on to these floors. This soil will be elevated by the conveyer bars 25 and will be dragged along the floors until openings 65 and 66 have been reached at the top of these inclined floors. It is evident that at these 90 points the soil will be scraped from the floor and will fall through the openings at the sides of the ditch, thus rebuilding the ditch and its banks and increasing its depth, as particularly shown in Fig. 3 of the drawings. During the operation of the device 100 the stabilizer plates 47 and 48 will be raised or lowered as the case may be to insure that the mechanism will be in proper alignment and will act to cut straight ditch walls of 105 equal angles. In case a change in the course of travel is contemplated, the steering wheel 61 may be rotated and this in turn will swing the rudder 59 in a manner to divert the prow of the machine from its original 110 course of travel.

Thus we have produced a ditch cleaner, the leading features of which are a body in the form of a boat and adapted to be drawn along a ditch and restore it to the desired 115 shape, a prow extending forwardly from the body and having a bottom cutting edge and a vertical center cutting edge, a rudder under the prow for directly guiding the 120 prow and body, side cutters extending upwardly and outwardly in front of the body, floors behind the side cutters for shaping the banks of the ditch, means for scraping the loose material upwardly and outwardly 125 over the floors, and adjustable stabilizers 130

for guiding and holding the body in a desired upright position.

It will thus be seen that the device here disclosed will act in a positive and effective manner to rapidly clean and rebuild irrigation ditches and the like and that the results here described will be attained entirely by mechanical operation.

While we have shown the preferred construction of our irrigation ditch cleaner as now known to us, it will be understood that various changes in the combination, construction, and arrangement of parts may be made by those skilled in the art without departing from the spirit of our invention.

We claim:

1. In a ditch cleaner, a body in the form of a boat, a prow extending forwardly from the body and having a bottom cutting edge and a vertical center cutting edge, a rudder under the prow for directly guiding the prow and body, side cutters extending upwardly and outwardly in front of the body, floors behind the side cutters, and means for scraping loose material upwardly and outwardly over the floors; the cross-sectional shape of the body and floors being adapted to produce the desired cross-sectional shape in a ditch.
2. In a ditch cleaner, a body in the form of a boat, a prow extending forwardly from the body and having a bottom cutting edge and a vertical center cutting edge, a rudder under the prow for directly guiding the

prow and body, side cutters extending upwardly and outwardly in front of the body, floors behind the side cutters, means for scraping loose material upwardly and outwardly over the floors; the cross-sectional shape of the body and floors being adapted to produce the desired cross-sectional shape in a ditch; plates pivotally connected to the sides of the body and extending outwardly and upwardly and adapted to rest upon the banks of a ditch, and means for adjusting the plates to hold the body in a desired upright position.

3. A ditch cleaner comprising a body in the form of a boat and adapted to be drawn along a ditch and restore it to a desired shape, a prow extending forwardly from the body and having a bottom cutting edge and a vertical center cutting edge, a rudder extending downwardly from the prow to travel in the earth and directly guiding the prow and body, side cutters extending upwardly and outwardly in front of the body, floors behind the side cutters for shaping the banks of a ditch, means for scraping loose material upwardly and outwardly over the floors, and adjustable stabilizers for guiding and holding the body in a desired upright position.

In testimony whereof we have signed our names to this specification.

HENRY M. QUINCEY.

FREDERICK J. SIENKNECHT.

MICHAEL J. DONAHOO.
